UNITED STATES PATENT OFFICE

WILLIAM HUGHES, OF MCKEES ROCKS, PENNSYLVANIA

PANTOGRAPH

Application filed December 23, 1927. Serial No. 242,192.

This invention relates to pantographic devices, and the general object of the invention is to provide an appliance of this nature which may be used in the open, as it were, for the purpose of drawing or sketching objects in the open and reducing them to the dimensions of the drawing sheet.

A further object is to provide a device of this character having a movable sight forming part of the pantograph itself, and a fixed sight to which the draftsman applies his eye, and in this connection to provide a bracket for supporting the fixed sight at a proper distance from the movable sight on the pantograph.

A still further object is to so construct the movable sight of the pantograph that it will form part of the hinge connection between two arms of the pantograph, and further to provide a transparent window having a sighting mark therein through which the object being drawn may be observed.

Other objects will appear in the course of the following description.

My invention is illustrated in the accompanying drawings, wherein:

Figure 1 is a front elevation showing my improved pantograph applied;

Figure 2 is a vertical section on the line 2-2 of Figure 1, the rotatable joint of the pantograph being shown in section;

Figure 3 is an enlarged face view of the window and joint for the pantograph;

Figure 4 is a like view to Figure 1 but looking from the rear;

Figure 5 is a fragmentary section through the rings which form the rotatable joint shown in Figure 3;

Figure 6 is a section through the bracket and the pantograph arm engaged therewith;

Figure 7 is a fragmentary elevation of one end of one of the pantograph arms with the tracer thereon;

Referring to these drawings, it will be seen that my pantographic appliance comprises the longitudinally extending straight edge 10, which may be made of wood or any other suitable material, and which is provided with the right angularly projecting portion 11. The part 11 is attached to the straight edge

10 intermediate the ends of the straight edge, and the parts 10 and 11 are intended to be applied over the drawing or the drawing board upon which the sheet of paper is carried so that the part 10 will be parallel to the upper edge of the board and the part 11 parallel to one side edge thereof as, for instance, the left side edge. These parts 10 and 11 are provided with apertures 12 through which screws 13 may pass to hold the device in place upon the drawing board.

Mounted upon the left hand end of the straight edge 10 is a bracket 14 attached by screws to the straight edge, and pivoted to this bracket is one arm 15 of an ordinary pantograph. This arm is pivoted at 16 to a complementary arm 17 which extends upwardly and laterally and is provided at its end with a tracer 18. This tracer or point may be in the form of a sheath enclosing a pencil point or may have any other suitable form and preferably has screw-threaded engagement with the arm of the pantograph so that it may be turned in one direction or the other so as to bring the point against the paper. Crossing the arm 15 is another arm 19 of the pantograph, and crossing the arm 17 is the arm 20 of the pantograph. It will be seen that the arms 19 and 20 are parallel to the arms 17 and 15 respectively and that the arms 19 and 20 are pivoted to the arms 17 and 15 respectively by the pivot screws 21 which may be in the form of small eye screws.

The arms 19 and 20 are pivotally connected to each other and the character of this pivotal connection forms a very important feature of my invention. As illustrated, the arm 20 has attached to its extremity a metal shank 22 which embraces the arm 20 and at its end is formed with an annulus 23. The arm 19 carries upon it a corresponding metal shank 24 which embraces the arm and which terminates in a metallic annulus 25. This annulus is made of thin metal and formed with radially extending lugs 26. Certain of these lugs are relatively short and are bent outwardly over the annulus 23. Certain other of the lugs are not only bent over the annulus 23 but are then again bent back to extend radially over a circular transparent

sheet 27 which may be cheaply formed of celluloid or like material. The lugs, therefore, hold the celluloid sheet in place so that this sheet oscillates with the annulus or ring 25. It will be seen that this provides for an oscillatory engagement between these two rings 23 and 25 and provides a pivotal engagement between these two arms 19 and 20.

10 The center of the celluloid window or sheet 27 is indicated by three radial marks 28, these marks being preferably of different colors so as to take away any dazzle or eye strain, and, though this is not necessary, the 15 celluloid sheet may be crossed by two series of parallel lines at right angles to each other so as to afford indicating lines.

It will be understood, of course, that each 20 arm of the pantograph will be provided with a series of holes through which the pins 21 may pass, and associated with these holes will be numerals which will indicate the manner in which the pantograph is to be adjusted and that by a proper adjustment of these 25 screws 21 the tracer or marker 18 may be caused to move in any desired proportion to the object being sketched.

In order to keep the eye of the draftsman 30 at a fixed point at all times while the drawing is being made, I provide a fixed peep sight which is at all times associated with the movable sight formed by the window 27. To this end, I attach to the frame formed by the members 10 and 11 and at the junction of 35 the member 10 with the member 11 a supporting bracket. In the present embodiment of the invention, this is formed of a strip of sheet metal bent so as to provide two downwardly and outwardly directed arms 40 29 and 30, these being spaced from each other at their inner ends to provide the flat base 31 which bears flat against the member 10 and is held thereto by a bolt 32 and wing nut 33. These two arms 29 and 30 extend 45 downward and forward, as before stated, and are at a 45° angle with relation to the members 10 and 11. One of the arms is formed with a longitudinally extending slot 34 and the other with an aperture, and a bolt 35 50 passes through the slot and aperture and carries a wing nut.

Mounted upon the extremity of these arms and held in place by the bolt is the peep sight 36, which is a disk of metal having a central aperture and having a shank 37 perforated for the passage of the bolt 35, this shank extending up between the two arms and being held in adjusted position by the bolt. The two arms are adjusted so as to bring the disk 55 of the peep sight 36 parallel to the face of the drawing board.

In the use of this device, the members 10 and 11 are attached to the upper and end margins of the drawing board, as shown in 60 Figure 1. Assuming that the pantograph

arms have been properly adjusted, the draftsman then looks through the peep sight 36 and the center or window 27 and at the object to be drawn. He then shifts the tracer 18 so that the center 28 of the window 27 will travel along an edge, shadow or other marking of the object he desires to draw, and as the center 28 of the window 27 moves along this line as, for instance, the outline of an object, the tracer 18 will trace upon the drawing board a line corresponding to the outline of this object. Inasmuch as the action of a pantograph is well known, it is not believed any further description is necessary, as the use of the device will be obvious from the drawings.

The advantages of this construction are that it permits a draftsman to draw from nature, if desired, or at any rate draw from a distant object, whether natural or artificial, 70 whereas the ordinary pantograph only permits the copying of a drawing either to a smaller or larger scale onto a drawing board. With my drafting device, it is possible to copy pictures from a distance or to draw a 75 distant landscape upon the drawing board, and in fine to transfer to a drawing sheet or board the outlines or other markings of any object, natural or artificial, either far distant or relatively close. If it were not for the 80 fixed peep sight, it would be difficult, if not impossible, to hold the eye steadily in one position. The drawing board, of course, is to be mounted so that this peep sight will be immediately opposite the eye in the natural 85 position of the draftsman and the peep sight thus acts to give a permanent station to the eye so that the drawing transferred 90 will be an accurate copy of the original scene.

I have found in practice that by marking the center of the window 27 by colored radial lines or markings that eye strain is relieved. By providing a relatively large window, the draftsman can see precisely what he is doing and has a good view of the whole or a large part of the object while the center of the window is traversing along the line selected by the draftsman. If this movable sight or window were opaque and simply had a relatively small central opening, it would be difficult to use the device, even though a particular outline could be seen, as only a minute portion of the object could be seen and confusion of the lines would result.

Attention is called to the fact that I have provided a very simple means for supporting the circular window 27, while at the same time securing a proper pivotal joint between the two arms 19 and 20. The slot in the arm 120 30 through which bolt 37 passes allows the peep sight to be adjusted at different angles, while the bolt 37 allows the peep sight to be shifted around the bolt and to be held in any desired adjusted position.

It will be seen that the device is very simple, may be cheaply made, and that the provision of the peep sight renders it extremely accurate and secures true perspective effects, where without this peep sight the perspective would be liable to be distorted. The bracket 29 is made adjustable, as when the pantograph is adjusted to the lower numbers it may be necessary to extend or lower the peep sight, or after the easel, drawing board and paper are set, a slight adjustment up or down or around, of the peep sight, will save the necessity of resetting the easel. It gives the person operating the pantograph more choice and freedom than would otherwise be the case.

I claim:—

1. A pantograph including two members disposed at right angles to each other adapted to be disposed against the corner of a drawing board, one of said members being extended beyond its junction with the other member, two elements pivoted to each other, one of said elements being operatively pivoted upon the extended end of the last named supporting member and the other element extending over the drawing board and carrying at its extremity a tracer, the pantograph including two other elements crossing the first named elements respectively and adjustably pivoted thereto, said second named elements of the pantograph at their other ends being joined by annuli having rotative engagement with each other, the annuli defining a central sight opening, a disk of transparent material disposed in said opening and having its center indicated thereon, and a bracket disposed at the junction of the two elements, the bracket extending outward approximately at an angle of 45° to the first and second named elements and having a peep sight disposed in approximate alignment with said sight opening, said peep sight and bracket being adjustable to bring the peep-sight in proper relation to the drawing to be made and to the central sight opening.

2. In an attachment of the character described, two coaxing pantograph arms, one of said arms carrying at its end a metallic annulus, the other of said arms carrying a metallic annulus having inwardly extending lugs, certain lugs being bent over the first named annulus to thereby provide for rotative engagement of the annuli with each other, and a transparent circular disk disposed upon said lugs and over which the extremities of certain of the lugs are bent, said disk having a central point indicated thereon.

3. A pantograph attachment for drawing boards comprising a supporting element adapted to be mounted upon a drawing board, a peep-sight mounted upon the supporting element, a pantograph comprising pivoted crossed elements, one of said elements being operatively pivoted upon said

supporting element, another element of the pantograph extending over the drawing to be made and carrying a tracer, the pantograph having two elements crossing the first named elements and pivotally connected to said elements respectively and to each other, said last named pivotal connection including a transparent sight disposed in approximately alined relation with the peep-sight.

4. A pantograph including two elements 75 conjoined by annuli, having rotatable engagement with each other, the conjoined annuli forming a sight opening, a support upon which the pantograph is mounted and a bracket coaxing with the pantograph and 80 mounted upon said support, said bracket having two arms, one of the arms being longitudinally slotted, a bolt passing through the end of one arm and through said slot, and a peep-sight having an angularly disposed portion insertible between the extremities of said arms and through which the bolt passes, and means for supporting the bracket for bodily 85 rotative movement on an axis at right angles to the sheet upon which the drawing is to be 90 made.

In testimony whereof I hereunto affix my signature.

WILLIAM HUGHES.
